Inventor,

Charles J. Kintner

UNITED STATES PATENT OFFICE.

CHARLES J. KINTNER, OF PHILADELPHIA, PENNSYLVANIA.

SKATE-ROLLER.

SPECIFICATION forming part of Letters Patent No. 404,547, dated June 4, 1889.

Application filed April 11, 1887. Serial No. 234,451. (No model.)

To all whom it may concern:

Be it known that I, CHARLES J. KINTNER, formerly of Washington, District of Columbia, now residing in Philadelphia, Pennsylvania, have made certain new Improvements in Roller-Skates, of which the following specification, taken in connection with the accompanying drawings, is a full, clear, and exact description.

10 My invention relates particularly to improvements in the rollers of roller-skates and analogous devices, and has for its object the prevention of oil used in oiling said parts from running or dripping on the floor; and to 15 this end it consists, first, in providing said rollers with retaining-grooves on their lateral faces filled with absorbent material to catch the oil as it runs from the axles of the skates down or over said lateral faces; second, in 20 providing an absorbent packing to hold against the faces of the rollers either by devices to be hereinafter described or by its own inherent properties.

Prior to my invention, so far as I am aware, 25 no provision was ever made for common and well-known forms of skating-rollers whereby oil could be kept from trickling down onto the face of the roller and ultimately to the floor of the rink, thereby soiling the floor and also 30 endangering the skater.

I am aware that self-oiling rollers have been provided with retaining-cups and packing for the purpose of retaining the oil; but my invention has especial reference to well-known 35 forms of rollers which may be oiled while being used by simply dripping the oil on the end of the roller-axes in a manner well understood.

In the drawings, Figure 1 is a side elevation 40 of a skating-roller, part broken away to show my improvement. Fig. 2 is a cross-section of Fig. 1. Fig. 3 is a cross-section, and Fig. 4 a side elevation, showing a modified form with packing and retaining-ring. Fig. 5 is an elevation showing the packing wound about a retaining-ring. Fig. 6 is a cross-section of a roller, showing an additional modification with two grooves on each face and felt or other rigid absorbent material in place, no retaining-ring being required.

Referring now to the drawings by detail, A

represents a skate-roller, and B the body thereof. In its lateral faces are cut two grooves C, of sufficient depth to hold such oil as may trickle down from axle G.

55 R is a spring-ring of such size that it will retain the absorbent packing P, Figs. 1, 2, 3, and 4, in place. This packing may be of any absorbent material, and may be either wrapped around the ring, as shown in Figs. 60 1, 2, and 5, or may lie in the grooves and be held in place by the ring resting directly upon it, as shown in Figs. 3 and 4. In Fig. 6 is shown a modified form of packing, 65 consisting of thick felt or other equivalent absorbent material—as sponge, cork, porous rubber, &c.—which is of sufficient body to sustain itself in place when forced into the grooves C C', and may, if desired, have a slit S to allow it to be easily forced into grooves C'. 70

O O are oil-holes to afford free access for the oil to the axle G.

E is the linchpin, and F the washer, of well-known forms.

g is an additional groove for oiling purposes, 75 as will be explained.

The operation is as follows: On oiling the skate, in the usual manner, by pouring oil upon the end of axle G and about washer F, it runs in between the roller and axle, but 80 more or less waste occurs, and after the skater has been skating a brief time the oil is forced by centrifugal force along the lateral faces of the roller in radial lines. By my improvement the absorbent takes it up and holds it, so that 85 it cannot pass to the floor. When the absorbent material has become thoroughly saturated with oil, it may be removed, and when sufficient quantity of such material has collected it may be put in an oil-press and the 90 oil removed, thus saving oil which was before wasted.

It will be observed that the outer ends of oil-holes O O, Fig. 6, enter a groove g, which runs entirely around washer F. This groove 95 is to catch the oil from the can and direct it toward the oil-holes, and may have an ogee shape similar to groove C, if desired, so as to keep as much oil as possible away from the absorbent P or second groove C. It will be 100 observed that this groove lies entirely without washer F, so that all the oil poured upon the

end of axle G and washer F will either go directly inside or find its way to said groove and ultimately inside, leaving small opportunity for any oil to drip onto the absorbing material or run into the second groove C.

5 In place of the grooves, I may simply cut a lateral ring-groove on each face of the roller of sufficient depth to hold the absorbent material and then glue said absorbent material 10 directly in such groove when the roller is made. Each roller so made would be complete and the felt would not be changed. Such form, however, I do not prefer, but merely describe it as an equivalent which may 15 be used, my most desirable form being that which utilizes the felt self-retaining packing and the oil-holes and groove.

I do not limit myself to the use of this improved oil-retaining device with skate-rollers, 20 as it obviously has many other analogous uses, as in band or belt pulleys, truck-wheels, and kindred devices.

Having thus fully described my invention, what I desire to secure by Letters Patent of 25 the United States is—

1. In a roller-skate, a roller having grooves in its lateral faces and absorbent material

located in said grooves for retaining the waste oil, substantially as described.

2. In a roller-skate, a roller having grooves 30 in its lateral faces, absorbent material in said grooves, and means for retaining said absorbent material in place, substantially as described.

3. In a roller-skate, a roller having grooves 35 in its lateral faces for catching the drip from the axle, in combination with oil-ducts running toward the center of the wheel, substantially as described.

4. In a roller-skate, a roller having grooves 40 in its lateral faces, with absorbent material located therein, in combination with oil-ducts for conducting the oil to the axle of the skate.

5. In a roller-skate, a roller having grooves 45 in its lateral faces for retaining the oil-drip, in combination with an oiling-groove and oil-ducts, substantially as described.

In testimony whereof I set my hand this 11th day of April, 1885.

CHARLES J. KINTNER.
